TOM BIGGS WILKINSON, OF BLACKSTON, ARNSIDE, ENGLAND

DRIVING GEAR OF JIGGING CONVEYERS

Application filed May 31, 1930, Serial No. 458,243, and in Great Britain June 18, 1929.

This invention relates to driving gear of jiggling conveyers such as are used at the coal face in collieries and for other purposes.

I have found that the efficiency and capability of jiggling conveyers may be increased to a remarkable extent, especially for conveyance up an incline, if the troughing of the conveyer is driven so that there is a dwell or period of rest at the end of the backward movement of the troughing. Although it has been proposed to drive the troughing of a jiggling conveyer from a prime mover through a single-acting toggle, no means have hitherto been provided for giving a dwell or period of rest in accordance with the present invention and the utility of this feature has not heretofore been appreciated.

According to the present invention, the troughing of a jiggling conveyer is driven by 20 or through mechanism which is so constructed and arranged that at the end of the rearward stroke of the troughing, the latter remains stationary, or substantially stationary, for a short but definite period before the 25 next forward stroke or impulse takes place. Preferably such mechanism comprises a single-acting, or substantially single-acting, toggle which is so arranged and adapted for actuation by the prime mover as to cause the 30 requisite dwell or period of rest referred to at the end of the backward stroke of the troughing.

The dwell or period of rest may vary according to the materials to be conveyed, the 35 speed of reciprocation and stroke of the troughing and other conditions, such as the amount of upward inclination (if any) of the conveyer. In, for example, the conveyance of coal or similar substances, a period of dwell 40 or rest corresponding to between one-quarter and one-third of the period of each cycle of reciprocation of the troughing gives effective results, the troughing having a stroke of about four inches and being reciprocated at 45 about 105 revolutions per minute. Under such conditions, it has been possible to convey blocks of lead or any solid materials or objects up an incline of 1 in 6, while sand and 50 other granular materials also are effectively

conveyed up inclines far in excess of those possible with the jiggling conveyers heretofore proposed.

The invention is hereinafter described by way of example with reference to the accompanying diagrammatic drawings, in which:

Figure 1 is a plan view illustrating one construction of driving gear according to the invention, in which the prime mover is a rotary compressed air engine;

Figure 2 is a transverse section on the line 2—2, Fig. 1;

Figure 3 is a transverse section on the line 3—3, Fig. 1;

Figure 4 is a side elevation on a smaller scale showing the method of holding the engine bed-plate and troughing supporting cradles in position;

Figure 5 is a plan view corresponding to Figure 4;

Figure 6 is a sectional view illustrating a modified construction of driving gear employing a belt and gearing; and Figure 7 is a plan view illustrating a further modification, in which the prime mover is a reciprocating compressed air engine.

The conveyer troughing A is mounted on cradles B which may be of any suitable construction, but preferably are constructed as described in the specification of my companion application Ser. No. 458,244 filed herewith. A bracket a is fixed on the underside of the troughing A (Fig. 4) and a rod a' is fixed at one end to the bracket a and at the other end to a link C mounted so that it can reciprocate in a direction parallel to the troughing, in guides c fixed to a plate d carried by a channel-shaped member D bolted or otherwise secured to an angle plate D' forming the support for the driving gear and which is held in position by props or piles E which are wedged between the bottom flange of the plate D' and the roof of the mine working.

A single-acting toggle F (Fig. 1) has one of the toggle arms F' pivotally connected at c' to the free end of the link C and the other toggle arm F² pivotally mounted on a fixed stud d' carried on a bracket d² fixed to an

angle plate D² bolted or otherwise fixed to the plate D'.

The common pivot f' of the two toggle arms F', F² is connected by a rod G with a pin g on the end of a crank G' mounted on a short vertical shaft on which is fixedly mounted a pinion g² driven through suitable gearing or through a gear box from a rotary compressed air engine H. The engine and gear box are supported by channel-shaped members h fixed to the plate D'. The pin g may be mounted eccentrically on a disc instead of on a crank. With the mechanism arranged as described and shown, the troughing will remain stationary, or substantially stationary, at the rear end of its stroke for a period of about one-quarter of each cycle of reciprocation of the troughing.

For the purpose of increasing the period of dwell or rest, for example, to about one-third of the cycle of reciprocation, the distance between the centre of the pin g on the crank G' and the centre of the pivot f' (i. e. the length of rod G), may be increased so that when the pin g is in the position nearest to the line joining the centres of the pivots c', d' of the two toggle arms, the centre of the pivot f' will have moved a short distance beyond the aforesaid line, thus increasing the free, or substantially free, motion of the linkage at the end of the backward stroke of the troughing.

The angle plate D' forming the base for supporting the engine H and the gearing is held in position by four or more props or piles E (Fig. 4) arranged along one side of the troughing so that there is no distortion of the bed-plate as when corner propping is used at each corner of a rectangular bed-plate, and consequently the base plate is more easily fixed and maintained in position.

Instead of driving the toggle F through gears from a vertical motor, as in Figures 1 to 5, it may be driven by a belt and pulley, as shown in Figure 6. In this arrangement the belt pulley L is mounted on a shaft l on which is also mounted a bevel pinion l' gearing with the teeth of a horizontal bevel gear i². This bevel gear carries a disc E³ carrying the pin g on which the end of the link G is mounted.

Figure 7 shows in plan another arrangement for driving the troughing. In this arrangement the end of the link or rod G is pivotally connected to the piston rod m of a double-acting compressed air engine M, and also to the toggle, as shown, and extends at an acute angle which more closely approximates a right angle than in the form of Fig. 1.

In the arrangements hereinbefore described with reference to the accompanying diagrammatic drawings, the rod connecting the toggle to the prime mover is preferably disposed at a suitable angle less than 90° with respect to the toggle arm the outer end of

which is fixed, when the toggle arms are in the same straight line, or substantially so. With such an arrangement, the speed of movement and the character thereof, as regards acceleration and deceleration, is different in the forward and backward stroke of the troughing and generally it is preferable to arrange the prime mover to rotate in such a direction that the quicker or more sudden movement is on the backward stroke. A subsidiary advantage of the driving gear according to the invention resides in the fact that during the period of dwell or rest no back shocks upon the conveyer can be communicated to the prime mover, as such shocks are transmitted directly through the aligned toggle arms and are taken by the fixed member or abutment by which the outer end of one of the toggle arms is located. This contributes to better service from the prime mover and the mechanism interposed between it and the toggle.

What I claim is:—

1. Driving gear for jiggling conveyers comprising, in combination, a frame presenting fixed supporting members; a single-acting toggle having one arm pivoted at its end to the frame; a reciprocating link connecting the other arm to the troughing; a guide bearing for the link on one of the supporting members; a connecting rod pivoted to the toggle at the pivot connecting the toggle arms; and a crank for driving the connecting rod, the connecting rod being so arranged that when the toggle arms are in substantial alinement, the crank pin is disposed between, and on the line through the centre of the crank and the centre of the pivot between the toggle arms, so that, during a considerable part of each revolution of the crank pin, substantially no movement will be imparted to the troughing.

2. Driving gear as claimed in claim 1 wherein the driving mechanism is so arranged that during the period of dwell or rest the common pivot of the two toggle arms passes a short distance beyond the line joining the centres of the pivots at the outer ends of the arms, for the purpose and substantially as described.

3. Driving gear as claimed in claim 1 wherein the connecting rod between the crank pin or the like and the toggle is arranged at a suitable angle less than 90° with respect to the toggle arm, the outer end of which is pivoted to the fixed member or abutment, when the toggle arms are in alinement.

4. Driving gear as claimed in claim 1 wherein the toggle is connected to the troughing by means of a link fixed to the underside of the said troughing and mounted so as to reciprocate parallel therewith.

5. Driving gear as claimed in claim 1 wherein the dwell or period of rest corre-

sponds to about one-quarter of the cycle of reciprocation.

6. Driving gear as claimed in claim 1, wherein the connecting rod is at an acute angle to the axis of the toggle arms when the toggle arms are in alinement.
